Patented Mar. 15, 1921.

UNITED STATES PATENT OFFICE.

ARTHUR F. NESBIT, OF WILKINSBURG, PENNSYLVANIA.

ART OF ELECTRICAL PRECIPITATION.

1,371,995.

Specification of Letters Patent. Patented Mar. 15, 1921.

Application filed December 10, 1920. Serial No. 429,666.

To all whom it may concern:

Be it known that I, ARTHUR F. NESBIT, a citizen of the United States, and resident of Wilkinsburg, in the county of Allegheny 5 and State of Pennsylvania, have invented certain new and useful Improvements in the Art of Electrical Precipitation, of which the following is a specification.

This invention relates to the separation 10 of solid or liquid particles from fluid streams by electrical precipitation, and more particularly to an apparatus of the refrigeration, successive stage, down flow type of electrical precipitator, and has for its principal object the cleaning and recovery of 15 coal-tar by-products from producer and coke oven gases.

Separation of particles from gaseous or 20 liquid streams by electrical precipitation methods involves the formation of an ionization field produced by opposing electrode systems, the fields being produced in various ways and generally being in the form of discharge and collecting electrodes between 25 which the field is produced.

Gaseous fluids such as producer gases and 30 by-product coke oven gases have a very high temperature and carry quantities of coal-tar and other by-products in suspension in the form of finely divided or vaporized particles of liquid and it is the object of the present invention to commercially recover the coal-tar and associated ingredients such as 35 anthracene and naphthalene separately from the gases by reducing the finely vaporized particles of these ingredients to a denser form by refrigeration and by subjecting them to the action of successive ionization zones and also by causing a mechanical 40 centrifugal action.

The apparatus for accomplishing the above objects is comparatively simple in construction, cheap to manufacture, and durable, as will be readily apparent from the 45 following specification and accompanying drawing herewith.

Figure 1 is a sectional, somewhat diagrammatic partial side elevation of tower-shaped apparatus embodying the principles of my 50 invention.

Fig. 2 is a continuation of the side elevation of Fig. 1 from the line X—X.

Fig. 3 is a detail of a portion of one of

the discharge electrodes showing the circular discharge edges. 55

Fig. 4 is a similar detail view showing a modified form of discharge electrode.

Referring to the drawings, the numeral 2 indicates a casing or shell having an insulating chamber 3 at its top, a suitable partition 4 acting as a support for the insulators 3^a etc., and the insulators 3^a carrying the electrode system, which includes supporting members 5 of proper form, having a depending support 6 and carrying member 7, 60 which preferably is in the form of a spider or frame and supports or carries the discharge electrodes 8 which extend centrally through tubular collecting electrodes 9.

The support 6 is a conductor and carries 70 the charge to the discharge electrodes 8, and is provided adjacent its lower end with collars 6^a having a plurality of discharge points. The points of the collars 6^a set up a discharge from their ends, which may be 75 identified as an electric wind, and which will throw back any of the gases or fogs formed by the gases thereby compelling them to pass downward through the electrode system.

The discharge electrodes 8 are in the form 80 of rods or small pipes, having several portions, each portion being of less diameter than its immediate preceding portion. The collecting electrodes 9 are likewise successively reduced in diameter to correspond 85 with the reduced diameter of the discharge electrodes 8, thus substantially equalizing the distance between the electrodes 8 and 9 throughout the entire system, so that the resistance to the travel of the electric discharges will be substantially equalized. 90 However, the collecting electrodes are not integral, but are formed of separate tube sections, each section being of less diameter than the preceding section and being arranged so that the smaller section telescopes an appreciable distance within the preceding larger section, thus forming outlets or traps 10 to permit the escape of the collected matter from the section of electrode immediately 95 preceding or above the trap.

Transverse conical shaped partitions 11 are arranged immediately below each of the series of traps formed in the collecting electrodes and are so arranged that their conical 105 peak is slightly below the lower edge of the

traps. These partitions 11 are adapted to gather or collect the product discharged through the traps 10 of the collecting electrodes. Suitable outlets or drains 11^a are 5 provided at the bottom edge of the partitions 11 to allow for the removal of the separated ingredients as desired.

A partition 11^b similar in construction and shape to the partitions 11 is arranged 10 slightly below the top edge of the collecting electrodes 9 and is adapted to collect any ash or dust particles which may be discharged over the top of the electrodes 9 due to the centrifugal action of the gases, as 15 they enter the tubular electrodes 9. The means for causing the centrifugal action of the gases and the release of the dust particles at this point will be hereinafter more fully described.

20 The discharge electrodes have circular edges 10^a thus forming fields composed of individual ionization zones arranged in the path of travel of the gases as they pass through the collecting electrode. It will be understood of course, that a helical screw 25 thread may be substituted for the circular edges 10^a if desired.

Suitable cooling or refrigerating jackets 30 are concentrically arranged around the collecting electrodes to cause condensation of the vapors as they are precipitated or hurled against the collecting electrodes and to generally lower the temperature of the gases as they traverse the ionization zones 35 formed in the spaces between the electrodes 8 and 9.

A direction imparting head or member 40 13 is arranged around and in contact with the upper end of each of the discharge electrodes and is secured to the spider 7. The members 13 are funnel shaped in the upper portion, and the lower portion is contracted more or less and provided with a plurality of vanes 14 forming a plurality of helical passages.

A part of the gases will be forced through 45 the helical passages formed by the vanes 14 and will have a centrifugal whirling motion imparted thereto, and will become ionized since the head members 13 are connected with and consequently charged with the same sign as the discharge electrodes. The remaining volume of gases will pass around the spider member 7 and direction imparting 50 head or members 13 and pass over the top of the collecting electrodes 9 where they will commingle with the portion that has passed through the helical passages and will thus take up the swirling motion of each portion 55 and also become charged. The whole volume of gas will then enter the space between the collecting and discharge electrodes.

60 A second spider member 15 is arranged to hold the lower ends of the discharge elec-

trodes 8, and when it is desired to further subject the gases to another set of ionization zones, as is generally the case, a second series 70 of discharge electrodes 16 are suspended from the spider 15 and are arranged to pass through a second series of tubular collecting electrodes 17. The centrifugal action of the gases is renewed immediately below the spider 15 by a second set of direction-imparting members 18 similar in all respects to the 75 members 13 and surrounding the discharge electrodes 16. It will of course be understood that the discharge electrodes 16 and collecting electrodes 17 are of successively smaller diameter similar to the electrodes 8 and 9, 80 and that suitable traps 17^a are provided for allowing the escape of the collected fluids from the collecting electrodes. Also that a conical partition 19 and outlets or drains 19^a 85 are arranged below the traps 17^a for the same purpose as the partitions 11 and drains 11^a are arranged below the traps 10. Suitable refrigerating jackets 12^a will also be arranged to surround the collecting electrodes, as described in the main structure. 90

The casing 2 is provided with a gas inlet 20 arranged above the upper ends of the collecting electrodes 9 and below the partition 4, the space between the partition and the tops of the electrodes forming a chamber 95 21 from which the gases pass into the several fields provided by the opposing electrode systems.

The space below the electrodes forms a collecting and discharge chamber 22 which 100 has a gas outlet 23 and a bottom discharge opening 24 closed by bells 25 of the usual construction.

The gases as they enter through the inlet 20 are laden with impurities principally 105 in the form of vaporized coal-tar products including pitch and tar, anthracene and naphthalene. There is also a certain amount of ash particles carried in suspension in the gases. 110

The tar and pitch, having a very high boiling point, will be the first ingredient or product to condense forming a fog of liquid particles of sufficient size to be precipitated by the centrifugal motion of the gases and a hurling force of the successive ionization zones. Therefore, the first tubular section 115 of collecting electrode will collect a tar and pitch substance, which it will discharge through its trap 10. 120

Anthracene, having the next highest boiling point to the pitch and tar, will be the ingredient next to condense and form a fog of fluid particles of sufficient size and weight to be precipitated, hence the second section 125 of the discharge electrodes 9 will collect an anthracene product.

Naphthalene, having the lowest boiling point of the three ingredients mentioned will be the last to condense the vapors of 130

this product and, therefore, the lower or last trap in the tubular electrodes will discharge a naphthalene product which has been gathered or collected in the collecting electrodes above the last or lowermost trap.

Detailed operations of the apparatus described, when cleaning producer and coke oven gases, is as follows:—

The gases laden with vaporized coal-tar products and carrying a small percentage of ash in the form of a solid enter the chamber 21 through the inlet 20, and a portion thereof will pass downward through the direction-imparting members 13, which, by reason of the helical construction of their vanes 14 10 impart a mechanical helical or centrifugal rotation to the gases, and said head members 13, being connected with, and therefore, charged with, the same sign as the discharge electrodes, will cause an initial ionization 20 of the gases passing therethrough. The other portion of the gases will pass around the spider member 7 and direction-imparting members or heads 13 and pass over the top 25 of the collecting electrodes where they will commingle with the portion that has passed through the helical passages and will take on the swirling motion of that portion and also become ionized since said first portion 30 has been subjected to an ionization force.

The rotation causes the heavier particles of dust to be thrown on the outside or periphery of the gas column due to centrifugal force, and since the gases are charged with the same sign as the discharge electrodes 8, 35 the ionization forces will aid in throwing off the dust particles before the gases enter the ionization zone between the discharge electrodes 8 and the collecting electrodes 9. The 40 ash particles thrown out at this stage will fall over and around the outside of the collecting electrodes and be gathered or caught on the transverse conical partition 11^a.

As the gases emerge from the members 13 45 and over the collecting electrode 9, they pass into the ionization zone between the discharge electrodes 8 and the collecting electrodes 9, and are immediately acted upon by the force of the ionization zones. The 50 heavier particles of liquid, which, in the case of coke oven and producer gases, will be particles of tar and pitch, are hurled or precipitated against the first sections of the collecting electrodes 9. As the gases pass on 55 through the first section of tubular collecting electrodes, they are gradually cooled, due to the action of the refrigerating jackets, and the finer particles of tar and pitch vapors are caused to condense, forming a fog of 60 fluid particles, and such particles are precipitated against the collecting electrodes 9.

The pitch and tar product which has been precipitated against the first sections of collecting electrodes 9 will flow or run downward on the inside of the electrode and es-

cape through the first series of traps 10 and be collected on the first conical partition 11, ready to be drawn off through the drains 11^a.

The gases continue to pass downward between the second section of the electrodes 8 70 and 9, and are further refrigerated causing the condensation of anthracene vapors which have a lower boiling point than the tar and pitch vapors, and which vapors will be condensed, forming a fog of anthracene particles, and will be precipitated, by the force of the ionization zones, against the second section of collecting electrodes. The anthracene precipitated in these sections of collecting electrodes will fall by gravity through 80 the traps 10 and be collected above the second conical partition 11, ready to be drawn off through the drains 11^a.

The gases pass on downward through the remaining space between the electrodes 8 and 85 9 and a portion thereof enter the second set of direction-imparting members 18, which are similar to the members 13, thus having a second whirling or centrifugal motion imparted to them, and they then pass between 90 the second series of discharge electrodes 16 and collecting electrodes 17. The remaining gases pass around the members 18 and into the spaces between the collecting electrodes 17 and discharge electrodes 16 and 95 commingle with the first named portion. Any vapors which have been condensed during the passage of the gases through the last portions of the electrodes 8 and 9 and through the heads or direction-imparting members 100 18 will be thrown off due to the helical swirl or centrifugal force of the gases before they enter between the electrodes 16 and 17. This liquid, when coke oven and producer gases are being treated, will be naphthalene and 105 will be thrown over and around the collecting electrodes 17 and fall by gravity onto the last or lowermost conical partition 19. The body of gases will continue their course 110 downward into spaces between the electrodes 16 and 17 and be subjected to a further refrigerating action to condense any remaining naphthalene vapors forming a fog of minute liquid particles which will be precipitated against the collecting electrodes, 115 due to the action of the force of the ionization zones.

These condensed and precipitated liquid particles will escape or flow through the traps 17^a onto the conical partition 19 and be 120 drained through the outlets or drains 19^a.

After the point has been reached where the naphthalene has been condensed and removed the gases are comparatively clean and they then pass out from the space between 125 the electrodes 16 and 17 into the chamber 22 and escape through the outlet 23. Any particles which may be precipitated by the ionization action of the electrodes below the traps 17^a will be collected into the bottom of 130

the chamber 22 and removed through the discharge openings 24 which are normally closed by bells 25.

If it is desired or found beneficial, suitable spray nozzles may be located in the path of flow of the gases at a point above the lower spider members 15 and a liquefied naphthalene product sprayed into the gases to form a nucleus to aid in the gathering of the finer naphthalene particles contained in the gaseous fluids being cleaned.

Experience has shown that, by proper adjustment with regard to the length of the different collecting electrode sections and the amount of refrigeration applied, commercially pure pitch and tar, anthracene, and naphthalene may be separately obtained at the various stages of the apparatus above described.

While I have described my apparatus as being particularly adapted to the cleaning and separation of by-products from producer and coke oven gases, it will be, of course, understood, that I do not wish to be limited to this specific application of the apparatus since it may be advantageously used to clean other gases or fluids and to separate other ingredients than the ones named.

I claim:

1. Apparatus for removing and separating vaporized products from gaseous fluids comprising a casing, opposing electrode systems within said casing, having a discharge electrode and a tubular collecting electrode, said electrode systems being adapted to form ionization fields therebetween for precipitating the vaporized products, a plurality of spaced traps formed along the length of each of said collecting electrodes and refrigerating jackets surrounding said collecting electrodes to lower the temperature of the gases and cause condensation of the vaporized products.

2. Apparatus for removing and separating vaporized products from gaseous fluids comprising a casing, opposing electrode systems within said casing, having a discharge electrode and a tubular collecting electrode, said electrode systems forming a plurality of ionization fields therebetween for precipitating the vaporized products, a plurality of spaced traps formed along the length of each of said collecting electrode and refrigerating jackets surrounding said electrodes, and means located below each of said series of traps for collecting and dispensing the precipitated products discharged through said traps.

3. An apparatus of the class described comprising a casing having inlet and outlet ports, a supporting structure within said casing, opposing electrode systems within said casing having discharge electrodes and tubular collecting electrodes, said discharge electrodes being progressively reduced in di-

ameter toward their lower ends and being supported and mounted in said supporting structure, said tubular collecting electrodes being composed of a plurality of sections, each of said sections being of less diameter than their immediate preceding sections, and telescopically extending within the preceding section an appreciable distance, said telescopic portions of said collecting electrodes, forming traps through which the collected products are adapted to flow, refrigerating jackets surrounding said electrodes and conical transversely extending walls arranged below each of said series of traps adapted to collect and retain the products discharged therethrough.

4. An apparatus of the class described, comprising a casing, having inlet and outlet ports, a supporting structure within said casing, opposing electrode systems within said casing, having discharge electrodes and tubular collecting electrodes, said discharge electrodes being progressively reduced in diameter, toward their lower end, and being supported and mounted in said supporting structure, said tubular collecting electrodes being likewise progressively reduced in diameter to correspond with the reduction in diameter of the discharge electrode, a plurality of spaced traps formed along the length of each of said collecting electrodes through which the collected products precipitated against the collecting electrodes are adapted to escape, refrigerating jackets surrounding said collecting electrodes, and conical transversely extending walls arranged below each of said series of traps adapted to collect and retain the products which escape through said traps.

5. An apparatus of the class described, comprising a casing, having inlet and outlet ports, a supporting structure within said casing, opposing electrode systems within said casing having discharge electrodes and tubular collecting electrodes, said discharge electrodes being progressively reduced in diameter toward their lower ends and being supported and mounted in said supporting structure, said tubular collecting electrodes being composed of a plurality of sections, each of said sections being of less diameter than their immediate preceding sections and telescopically extending within the preceding sections an appreciable distance, said telescopic portions of said collecting electrodes forming outlet traps through which the collected products are adapted to flow, refrigerating jackets concentrically arranged around each of said collecting electrodes, and means arranged below each of said series of traps adapted to collect and retain the products discharged therethrough.

6. An apparatus of the class described, comprising a casing, having inlet and outlet

ports, a supporting structure within said casing, opposing electrode systems within said casing, having discharge electrodes and tubular collecting electrodes, said discharge electrodes being progressively reduced in diameter, toward their lower end, and being supported and mounted in said supporting structure, said tubular collecting electrodes being likewise progressively reduced in diameter to correspond with the reduction of the discharge electrode, a plurality of spaced traps formed along the length of each of said collecting electrodes through which the collected products precipitated against the collecting electrodes are adapted to escape, refrigerating jackets surrounding said collecting electrodes, centrifugal head members mounted in said collecting electrodes, having a plurality of helical passages around their outer periphery through which the gases travel, and conical transversely extending walls arranged below each of said series of traps adapted to collect and retain the products which escape through said traps.

7. The method of separating vapor par-

ticles from a stream of gaseous fluids, comprising, first, imparting a mechanical centrifugal whirling motion thereto, then successively refrigerating said stream to condense liquid vapors held therein, forming a fog of liquid particles, subjecting said refrigerated stream to successive ionization zones to precipitate the liquid particles forming said fog, and collecting said precipitated liquid particles.

8. The method of separating vapor particles from a stream of gaseous fluids, comprising first, initially ionizing said stream and imparting a mechanical centrifugal whirling motion thereto, then successively refrigerating said stream to condense liquid vapors held therein, forming a fog of liquid particles, subjecting said refrigerated stream to successive ionization zones to precipitate the liquid particles forming said fog, and collecting said precipitated liquid particles.

In testimony whereof I have hereunto signed my name.

ARTHUR F. NESBIT.
